SCRAPER

Elmer A. Hyer, Modesto, Calif.

Application April 12, 1940, Serial No. 329,294

5 Claims. (Cl. 37—129)

This invention relates to a leveling scraper, my principal objects being to provide a scraper of this general type which will have great capacity for its size and weight, one which may be very easily and quickly controlled and which requires a minimum of power for such control; and one in which the bowl is so shaped that while it is capable of carrying a considerable load, it will discharge easily and completely without extreme lift and at any leveling angle of the bowl so that very close leveling may be effected, coupled with a complete discharge from the bowl, with a single setting or adjustment of the bowl.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a side elevation of the scraper with the bowl in a scraping position.

Figure 2 is a sectional elevation of the scraper with the bowl tilted to a full dump position.

Figure 3 is a top plan view with the bowl in the position of Fig. 1.

Referring now more particularly to the characters of reference on the drawings, the frame of the scraper includes horizontal side beams 1 connected at intervals by cross beams which include a relatively forward beam 2 and a beam 2a to the rear of the same. The beams 1 are parallel between beams 2 and 2a and then converge to a connection with a vertical clevis plate 3 adapted for supported connection at different levels with the drawbar clevis of a tractor as is common practice. The side beams at their rear end are supported by wheels 4 disposed outside said beams.

The side beams are braced against lateral or vertical deflection by an upstanding truss structure which comprises pairs of brace beams 5 projecting upwardly from the side beams 1 at their rear end and adjacent cross beam, in converging relation to each other both laterally and longitudinally of the frame to a central apex above the side beams substantially midway between the cross beams 2 and 2a. A central longitudinal brace beam 6 extends from said apex forwardly to a connection with plate 3. Another central beam 7, which serves both as a brace and as a means to support the hydraulic operating unit

hereinafter described if such is used, extends downwardly from said apex to a connection with cross beam 2a. In this manner relatively light and widely spaced side beams may be used, while maintaining the frame amply rigid for hard service and relatively heavy loads.

Disposed in the frame between beams 2 and 2a and under the braces 6 and 7 is the bowl. This includes relatively long side plates 8 and a bottom plate 9 extending rearwardly and upwardly on an easy curve from the depending blade 10 to a point near the top of the side plates, from which point upwardly the curvature becomes more abrupt and practically vertical. The side plates project ahead of the blade some distance so as to form dirt deflecting wings.

The bowl is mounted at its forward end in connection with the side beams 1 by tension arms 11 which are rigidly secured on the inner face of the side plates and project forwardly from the same a short distance at a level well below the center of height of the bowl.

At their forward end, the arms are pivoted as at 12 on ears 13 rigid with and depending from beams 1 just rearwardly of cross beam 2. The axis of swinging of the bowl is thus relatively low and close to the blade, so that comparatively little tilting movement of the bowl will suffice to withdraw the blade from the ground and place the same in a leveling position.

This specific mounting arrangement also distributes the weight of the load so that a minimum of power applied to the bowl at its rear end, will suffice to tilt the same upwardly to control the leveling position of the blade.

A conventional cable control may be used for the purpose, but for tractors equipped with a fluid pressure generating apparatus I preferably use the hydraulic unit shown. This comprises a hydraulic cylinder 14 extending lengthwise of and securely strapped or otherwise secured on the brace beam 7 on its back side. The piston rod 15, projecting from the upper end of the cylinder, is pivotally connected at its upper end to a pair of depending links 16 which are disposed on opposite sides of the cylinder and beam 5 and are pivoted at their lower end on ears 17 projecting from the bottom plate of the bowl a short distance from its upper end.

The bowl tends to drop of its own weight to a digging position, the depth of digging being controlled by the extent to which the piston is allowed to lower in the cylinder, and independently to some extent by altering the level on plate 3 at which connection is made with the tractor.

Owing to the specific upward incline of the bottom plate from the blade, even when the bowl is in digging position, the dirt will readily discharge from the bowl when the latter is tilted only sufficient to dispose the blade in a close leveling position relative to the ground.

The depth of the bowl is such that a considerable load of dirt may be actually carried free of the ground rather than being shoved bodily along as is generally the case with a leveler. This feature of course considerably reduces the load on the tractor and the strains on the scraper frame and other parts, and reduces loss of dirt by spillage from the sides when the dirt is being moved from the point of scraping to the point of discharge and leveling.

The truss structure projects above the side beams a sufficient distance to enable the back of the bowl to be raised so as to dispose the bowl at a steep angle if desired for very fast discharge, as shown in Fig. 2.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A leveling scraper comprising a frame supported for movement along the ground, a bowl hung in the frame for upward tilting movement at the rear, said frame including side beams and an upwardly extending truss structure including brace members converging to a central apex above the bowl from longitudinally spaced points in the length of the beams beyond the area occupied by the bowl.

2. A leveling scraper comprising a frame supported for movement along the ground, a bowl hung in the frame for upward tilting movement at the rear, said frame including side beams and an upwardly extending truss structure which includes a pair of longitudinal centrally disposed brace members converging upwardly to an apical connection from longitudinally spaced points on the frame and other brace members diverging

laterally and longitudinally of the frame from said connection to points on the side beams spaced longitudinally of the frame from each other and from the frame ends of the first named brace members.

3. A leveling scraper comprising a frame supported for movement along the ground, a bowl hung in the frame for upward tilting movement at the rear, said frame including side beams and an upwardly extending truss structure which includes pairs of brace members diverging from each other both laterally and longitudinally of the frame from an apex above and centrally of the width of the frame to connections with the side beams at longitudinally spaced points thereon, and a central longitudinal member extending forwardly from said apex to a connection with the frame ahead of the connection of the first named members with the side beams.

4. A scraper comprising a frame supported for movement along the ground, a bowl hung in the frame for upward tilting movement at the rear, a rigid member mounted on the frame rearwardly of the bowl and upstanding from the frame in clearance relation to said bowl, a hydraulic cylinder mounted on said member lengthwise thereof, a piston rod projecting upwardly from the cylinder, and a link pivotally connected at one end on the piston rod and depending therefrom to pivotal connection at its lower end on the bowl at the back; the upper end of the link overhanging the bowl and the lower end portion thereof curving forwardly to said pivotal connection with the bowl and in clearance relation to the back of the bowl.

5. A scraper comprising a frame supported for movement along the ground, a bowl hung in the frame for upward tilting movement at the rear, a rigid member mounted on the frame rearwardly of the bowl and upstanding from the frame in clearance relation to said bowl, a hydraulic cylinder mounted on said member lengthwise thereof, a piston rod projecting upwardly from the cylinder, spaced parallel links pivoted at one end on the piston rod and depending therefrom to pivotal connection at the other end on the bowl at the back; said member having a forward slope, and the links being disposed on opposite sides of said member and intersecting the same intermediate their ends.

ELMER A. HYER.
